UNITED STATES PATENT OFFICE.

HENRY J. KASCH, OF DAYTON, OHIO, ASSIGNOR TO THE KURZ-KASCH COMPANY, OF DAYTON, OHIO, A CORPORATION OF OHIO.

DESIGN FOR A POINTER KNOB FOR RADIO APPARATUS AND THE LIKE.

Application filed August 31, 1925. Serial No. 14,672. Term of patent 14 years.

To all whom it may concern:

Be it known that I, HENRY J. KASCH, a citizen of the United States, residing at Dayton, Montgomery County, Ohio, have invented a new, original, and ornamental Design for a Pointer Knob for Radio Apparatus and the like, of which the following is a specification, reference being had to the accompanying drawing, forming a part thereof.

Fig. 1 of the drawing is a perspective

view, Fig. 2 a front elevation and Fig. 3 a side elevation of a pointer knob for radio apparatus, showing my new design.

I claim:

The ornamental design for a pointer knob for radio apparatus and the like, substantially as shown.

In testimony whereof, I have hereunto set my hand this 15th day of June A. D. 1925.

HENRY J. KASCH.
